UNITED STATES PATENT OFFICE.

JOHN MATTHEWS, OF BRIDGENORTH, ENGLAND, ASSIGNOR TO ARNOLD,
CONSTABLE & CO., OF NEW YORK, N. Y.

DESIGN FOR A CARPET.

SPECIFICATION forming part of Design No. 22,616, dated July 18, 1893.

Application filed June 22, 1893. Serial No. 478,518. Term of patent 3½ years.

To all whom it may concern:

Be it known that I, JOHN MATTHEWS, a subject of the Queen of Great Britain, residing at Bridgenorth, Shropshire, England, have invented and produced a new and original Design for a Brussels Carpet, of which the following is a specification, reference being had to the accompanying drawing, making a part of the same, and which is sufficient to enable others skilled in the art to make and use my invention.

What I claim as new, and desire to secure by Letters Patent, is—
The design for a Brussels carpet, as shown in the accompanying drawing.

JOHN MATTHEWS.
